Fig. III.

UNITED STATES PATENT OFFICE.

GEORGE P. WIGGINTON, OF KALAMAZOO, MICHIGAN.

TEMPORARY BINDER.

1,010,556.

Specification of Letters Patent.

Patented Dec. 5, 1911.

Application filed April 8, 1911. Serial No. 619,724.

To all whom it may concern:

Be it known that I, GEORGE P. WIGGINTON, a citizen of the United States, residing at the city of Kalamazoo, county of Kalamazoo, State of Michigan, have invented certain new and useful Improvements in Temporary Binders, of which the following is a specification.

This invention relates to improvements in temporary binders.

The main objects of this invention are: First, to provide in a temporary binder or loose sheet holder, an improved adjusting mechanism. Second, to provide an improved binder or loose sheet holder of the binding core or strip type in which the tension on the binding strips is not materially varied by the opening or closing of the binder, or the swinging of the covers. Third, to provide in a temporary binder, an improved leaf clamping bar. Fourth, to provide an improved temporary binder by which any number of leaves up to the maximum may be effectively clamped and one in which the binder mechanism is so constructed that the covers may be made very thin. Fifth, to provide an improved binding mechanism which is particularly adapted for embodiment in light or small binders. Sixth, to provide in a temporary binder, an improved cover structure. Seventh, to provide an improved temporary binder which is very economical in structure and simple and easy to manipulate. Further objects, and objects relating to structural details, will definitely appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing, forming a part of this invention, in which:

Figure I is a perspective view of a structure embodying the features of my invention, the cover containing the binding mechanism being shown open, a portion of the other cover being broken away. Fig. II is a detail inside plan view of the structure shown in Fig. I, the leaves being shown in an upright position. Fig. III is an inverted detail of the binder adjusting mechanism.

Fig. IV is a detail longitudinal section through the cover containing the adjusting mechanism, taken on a line corresponding to line 4—4 of Fig. II. Fig. V is a detail section on line 5—5 of Fig. IV. Fig. VI is an enlarged detail section of the binder closed, taken on a line corresponding to line 6—6 of Fig. II. Fig. VII is an enlarged detail of the binder closed, taken on a line corresponding to line 7—7 of Fig. II. Fig. VIII is a detail longitudinal section with the covers swung back to back. Fig. IX is an enlarged detail corresponding to Fig. III of a modified construction. Fig. X is a detail section on line 10—10 of Fig. IX.

In the drawing, similar reference characters refer to similar parts throughout the several views, and the sectional views are taken looking in the direction of the little arrows at the ends of the section lines.

Referring to the drawing, the covers 1 and 2, in the embodiment of my invention illustrated, are formed of boards, such as binder's board, with an outer covering 3 of leather. At the inner ends of the boards 80 are cover bars 4 formed of sheet metal folded longitudinally upon the ends of the cover boards. The cover board of the cover 2 is cut away at its inner end to provide a cover recess 5. The folded edges of the cover bars 85 4 are curved to provide bearing knuckles 6 for the leaf clamping bars 7. These leaf clamping bars are in the form of flat strips of metal, and are disposed in bearing engagement with the knuckles of the cover 90 bars 4.

The clamping bars are provided with rearwardly projecting loop-like pintle members or knuckles 8, which project into openings 9 provided therefor in the cover bar 95 knuckles. These knuckle openings are deep enough to permit the leaf clamping bars to swing against either side of the cover bars.

The pintles 10 are arranged in the cover bars 4 to engage the clamping bar knuckles. The binding strips 11 are arranged through openings 12 provided therefor in the cover bars, and through aligned openings 13 in the leaf clamping bars. The openings 12 in the cover bars are deep enough so that the 100 binding strips swing freely therein, no matter what position the clamping bars may assume relative to the covers.

The binding strips are secured to the cover bar of the cover 1 by means of the 110

tongues 14, which are formed integrally with its cover bar, the tongues being V-shaped and deflected downwardly to engage the holes 15 in the ends of the binding strips. The cover board is provided with cavities or recesses 16 adapted to receive the ends of the binding strips, as is clearly shown in Fig. V. As the ends of these tongues engage the opposite arm of the bar when sufficient stress is applied to the binding strip, they are effectively supported so that, although the bars are formed of light sheet metal and the tongues made comparatively small, they are still capable, when thus positioned of sustaining very heavy strains. The binding strips are adjustably secured to the other cover by means of the ratchet bar 17, on which is slidably mounted the bar-like binding strip adjusting member 18. A pawl 19 is pivoted at 20 on the under side of the member 18 to coact with the rack bar. The outer end of the pawl 19 is extended laterally and turned up to provide a finger piece 21. This finger piece engaging the edge of the bar serves as a stop for the pawl in one direction. A stop 22 is provided for limiting its movement in the other direction. When the finger piece engages the edge of the member 18, the pawl is in its engaging position, and when it is at the stop 22, it is in its disengaging position.

A U-shaped spring 23 is mounted on the stud 24 by one of its arms, the other arm engaging the end of the pawl so that the spring serves to yieldingly hold the pawl in either position.

The bar 17 is arranged in the cover recess 5, it being supported by the arm or plate 25 on the cover bar, which is disposed at the rear of the recess with its inner end connected to the cover bar. The bar support 25 is provided with bar engaging tongues 28. In the structure illustrated, the arm is formed integrally with the bar. (See Fig. IV.)

The recess 5 is open so that the adjusting member 18 may be grasped for manipulation; that is, the binder is tightened by grasping the member 18 and pulling the same outwardly. The pawl being adjusted to its engaging position, retains the member 18 in its adjusted position. To release the binding mechanism, it is only necessary to shift the pawl to its disengaging position and pull the covers apart. The pawl 19 is provided with finger holds 27 on its front edge.

In the modified structure shown in Figs. IX and X, the member 18 is slotted at 29 and the pawl 19 is provided with a stud-like finger piece 30, arranged in the slot. In this form the ends of the slot are the stops for the pawl. This ratchet adjustment mechanism is a modification and adaptation of the

ratchet adjusting mechanism shown in the patent to Harry F. Bushong, dated Feb. 4, 1908, No. 878,340, and it is one of the objects of my present invention to simplify that mechanism and adapt it for light binders, or holders of the type here illustrated, in which the covers are thin and light, and the structure is simple and economical.

By arranging the clamping bars and their coacting members on the cover, as illustrated, I secure a binder in which the covers may be opened to their fullest extent, or manipulated, as desired, without varying the tension on the binding cords. This is of very great advantage in that the covers remain in their adjusted positions; that is, extended in the flat, as shown in Fig. II or closed or may be swung back to back as shown in Fig. VII, with no tendency to assume some other position. Further, by maintaining this constant tension, the binding strips are not unduly strained or stretched, as may be the case where the tension is varied by the manipulation of the covers.

My improved binder is very simple and economical, quickly adjusted, and as stated, is very compact and light in weight, so that my improvements may be embodied in light binders such as order holders or the like.

I have illustrated and described my improvements in detail in the form in which I have embodied them. While I am aware that various modifications and structural details are possible, I have not attempted to illustrate or describe such modifications herein, as they will be readily understood by those skilled in the art to which this invention relates.

Having thus described my invention, what I claim as new and desire to secure by Letters Patent is:

1. In a temporary binder, the combination with the covers comprising cover boards, there being a recess at the inner end of one of the boards, of sheet metal cover bars folded longitudinally to receive the inner ends of said cover boards, the folded edges of said bars being curved to provide knuckles and having binding strip openings therein, binding strips arranged through said openings, flat sheet metal clamping bars having binding strip openings in alinement with the binding strip openings of said cover bars arranged in bearing engagement with the cover bar knuckles and having knuckles thereon arranged in openings provided therefor in the knuckle portions of said cover bars, pintles arranged in said cover bars to engage said clamping bar knuckles, a ratchet bar arranged in said cover recess, a supporting bar for said ratchet bar arranged at the rear of said recess with its inner end connected to the cover bar, an adjusting member to which said binding strips are

connected mounted on said ratchet bar, and a pawl on said adjusting member coacting with said ratchet bar.

2. In a temporary binder, the combination with the covers comprising cover boards, there being a recess at the inner end of one of the boards, of sheet metal cover bars folded longitudinally to receive the inner ends of said cover boards, the folded edges of said bars being curved to provide knuckles and having binding strip openings therein, binding strips arranged through said openings, flat sheet metal clamping bars having binding strip openings in alinement with the binding strip openings of said cover bars arranged in bearing engagement with the cover bar knuckles and having knuckles thereon arranged in openings provided therefor in the knuckle portions of said cover bars, and pintles arranged in said cover bars to engage said clamping bar knuckles.

3. In a temporary binder, the combination with the covers comprising cover boards, there being a recess at the inner end of one of the boards, of cover bars folded longitudinally to receive the inner ends of said cover boards, the folded edges of said bars being curved to provide knuckles and having binding strip openings therein, binding strips arranged through said openings, and clamping bars having binding strip openings in alinement with the binding strip openings of said cover bars arranged in bearing engagement with the cover bar knuckles the knuckle engaging sides of said clamping bars being substantially flat from edge to edge.

4. In a temporary binder, the combination with the covers comprising cover boards, there being a recess at the inner end of one of the boards, of cover bars folded longitudinally to receive the inner ends of said cover boards, the folded edges of said bars having binding strip openings therein, binding strips arranged through said openings, a ratchet bar arranged in said cover recess, a support for said ratchet bar arranged at the rear of said recess with its inner end connected to the cover bar, an adjusting member to which said binding strips are connected mounted on said ratchet bar and a pawl on said adjusting member coacting with said ratchet bar.

5. In a temporary binder, the combination with the covers having curved knuckle members at their inner ends, said knuckle members being channel shaped in cross section and having binding cord openings in the edges thereof, binding strips arranged through said openings, clamping bars arranged in bearing engagement with said knuckle members, said clamping bars having loop-like rearwardly projecting knuckles thereon, said cover knuckle members having openings adapted to receive the

same; and pintles arranged in said knuckle members, the parts being disposed so that when the covers are open the clamping bars are permitted to lie against the rear sides of the cover knuckle members and when closed, 70 against their front sides.

6. In a temporary binder, the combination with the covers having curved knuckle members at their inner ends, having binding cord openings therein, binding strips arranged through said openings, clamping bars arranged in bearing engagement with said knuckle members, said clamping bars having loop-like rearwardly projecting knuckles thereon, said cover knuckle members having openings adapted to receive the same, and pintles arranged in said knuckle members, the parts being disposed so that when the covers are open the clamping bars are permitted to lie against the rear sides of 80 the cover knuckle members and when closed, 85 against their front sides.

7. In a temporary binder, the combination with the covers, of cover knuckle members said knuckle members being channel 90 shaped in cross section to receive the inner ends of the covers, binding strips connecting said covers, arranged through openings in said knuckle members; clamping bars arranged in bearing engagement with said knuckle members and having pivotal connection therewith, the knuckle engaging faces of said clamping bars being substantially flat from edge to edge, said clamping bar having openings for said binding strips 95 in alinement with the openings therefor in said cover knuckle members, the pivotal connections for said clamping bars to said cover knuckle members being arranged to permit the clamping bars to swing into 100 planes substantially parallel with the inner and outer sides of the covers.

8. In a temporary binder, the combination with the covers, of cover knuckle members; binding strips connecting said covers, arranged through openings in said knuckle members, clamping bars arranged in bearing engagement with said knuckle members and having pivotal connection therewith, the knuckle engaging faces of said clamping bars being substantially flat from edge to edge, said clamping bars having openings for said binding strips in alinement with the openings therefor in said cover knuckle members, the pivotal connections for said clamping bars to said cover knuckle members being arranged to permit the clamping bars to rest against the rear sides of said cover knuckle members when the covers are open and against their front sides when 110 the covers are closed.

9. In a temporary binder, the combination with the covers, of binding strips connecting said covers, cover knuckle members through which said binding strips are ar- 130

- ranged, and clamping bars through which said binding strips are arranged having bearing engagement with said cover knuckles, said clamping bars being substantially flat from edge to edge on their knuckle engaging sides, the binding strip openings of said cover knuckle members being of such size as to permit the complete movement of the covers from their closed position to their 10 back to back position without substantially varying the tension on the binding strips.
10. In a temporary binder, the combination with the covers, of binding strips connecting said covers, cover bearing members 15 through which said binding strips are arranged transversely, and clamping bars through which said binding strips are arranged having bearing engagement with said cover bearing members, said clamping 20 bars being substantially flat from edge to edge on their inner bearing member engaging sides, the binding strip openings of said cover knuckle members being of such size as to permit the swinging of the covers from 25 their closed position to their back to back position without substantially varying the tension on the binding strips.
11. In a temporary binder, the combination with the covers, having curved bearing 30 members at their inner ends, binding strips, clamping bars arranged in bearing engagement with said cover bearing members and pivoted thereto, the bearing member faces of said clamping bars being substantially flat 35 from edge to edge so that the clamping bars are free to swing against the front or the rear sides of said bearing members and into planes substantially parallel therewith.
12. In a temporary binder, the combination 40 with the covers, having channel shaped cover bars at their inner ends, provided with curved knuckle portions having binding strip opening therein, binding strips connecting said covers arranged through said 45 openings; clamping bars formed of flat strips of metal, having loop-like rearwardly projecting pintle engaging members, formed integrally therewith, said cover bar knuckles having openings adapted to receive the same, 50 and pintles arranged in said knuckles, the openings in said cover bar knuckles being of such depth as to permit the clamping bars to swing substantially parallel with the front and the rear sides of the cover bars.
55. 13. In a temporary binder, the combination with the covers, having channel shaped cover bars at their inner ends, provided with curved knuckle portions having binding strip openings therein, binding strips connecting said covers arranged through said 60 openings, clamping bars formed of flat strips of metal, having pintle engaging members thereon, said cover bar knuckles having openings adapted to receive the same, 65 and pintles arranged in said knuckles, the

openings in said cover bar knuckles for said binding cords and clamping bar pintle members being of such depth as to permit the clamping bars to swing against the front or the rear sides of the cover bars and into 70 planes substantially parallel therewith.

14. In a temporary binder, the combination with the covers, one of the covers being provided with a recess, binding strips extending between said covers, a ratchet bar 75 arranged in said cover recess, a bar-like adjusting member mounted on said ratchet bar, said adjusting member being provided with finger holds on its front edge, a pawl pivotally mounted on the underside of said 80 adjusting member to coact with said ratchet bar, said pawl being provided with a finger piece adapted to engage the edge of said adjusting member, and a U-shaped spring secured by one arm to said adjusting member, its other arm being arranged to engage the end of said pawl whereby said pawl is held yieldingly in its engaging or disengaging 85 position.

15. In a temporary binder, the combination with the covers, one of the covers being provided with a recess, of binding strips extending between said covers, a ratchet bar arranged in said cover recess, a bar-like adjusting member mounted on said ratchet bar, said adjusting member being provided with integral finger holds on its front edge, a pawl pivotally mounted on the underside of said 95 adjusting member to coact with said ratchet bar, said pawl being provided with a finger piece adapted to engage the edge of said adjusting member, and a U-shaped spring secured by one arm to said adjusting member, its other arm being arranged to engage the end of said pawl whereby said pawl is held yieldingly in its engaging or disengaging 100 position.

16. In a temporary binder, the combination with the covers, one of the covers being provided with a recess, binding strips, a ratchet bar arranged in said cover recess, an adjusting member mounted on said ratchet bar, said recess being open to permit the grasping of said adjusting member, a pawl pivotally mounted on said adjusting member to coact with said ratchet bar, and a U-shaped spring secured by one arm to said 110 adjusting member, its other arm being arranged to engage the end of said pawl whereby said pawl is held yieldingly in its engaging or disengaging 115 position.

17. In a temporary binder, the combination with the covers, one of the covers being provided with a recess, binding strips, a ratchet bar arranged in said cover recess, an adjusting member to which said binding strips are connected mounted on said ratchet bar, said recess being open to permit the grasping of said adjusting member, a pawl mounted on said adjusting member to coact with said ratchet bar and a spring for said pawl.

18. In a temporary binder, the combination with the covers, a binding strip, a 134

ratchet bar mounted on one of said covers, an adjusting member to which said binding strip is connected mounted on said ratchet bar, said adjusting member being provided 5 with an integral finger hold on its front edge, a pawl mounted on said adjusting member to coact with said ratchet bar, and a spring for said pawl.

19. In a temporary binder, the combination 10 of the cover board, a cover bar of sheet metal folded longitudinally to receive the end of the said cover board and having a binding strip opening in its folded edge, the said cover board being recessed in alignment with said opening to receive the end 15 of the binding strip, a binding strip arranged through said opening to project into said recess and a binding strip retaining tongue adapted to engage said binding strip 20 formed integrally with the front side of said cover bar.

20. In a temporary binder, the combination 25 of the cover board, a cover bar of sheet metal folded longitudinally to receive the end of the said cover board and having a binding strip opening in its folded edge, a binding strip arranged through said opening and a binding strip retaining tongue adapted to engage said binding strip formed 30 integrally with the front side of said cover bar.

21. In a temporary binder, the combination 35 of the cover, a cover bar of sheet metal folded longitudinally and having a binding strip opening in its folded edge secured to said cover, a binding strip arranged through said opening, and a binding strip retaining tongue adapted to engage said binding strip formed integrally with one side of said 40 cover bar said tongue being directed toward the outer end of the cover.

22. In a temporary binder, the combina-

tion with the covers, one of the covers being provided with a recess, a binding strip, a ratchet bar arranged in said cover recess, 45 an adjusting member mounted on said ratchet bar, and a pawl on said adjusting member, said recess being open to permit the grasping of said adjusting member, for the purpose specified.

23. In a temporary binder, the combination 50 with the covers, one of the covers being provided with a recess, a binding strip, a ratchet bar arranged in said cover recess, an adjusting member, mounted on said 55 ratchet bar and a pawl mounted on the under side of said adjusting member to coact with said ratchet bar, said pawl being provided with a finger piece disposed at the rear of said adjusting member.

24. In a temporary binder, the combination 60 with the covers, a ratchet bar mounted on one of said covers, an adjusting member mounted on said ratchet bar, said adjusting member being provided with an integral finger hold on its front edge, and a pawl mounted on said adjusting member and coacting with said ratchet bar.

25. In a temporary binder, the combination 70 with the covers, one of the covers being provided with a recess, a ratchet bar, a support for said ratchet bar arranged in said recess and having bar securing tongues, binding strips, a binding strip adjusting member mounted on said ratchet bar, and a pawl mounted on said adjusting member and coacting with said ratchet bar.

In witness whereof, I have hereunto set my hand and seal in the presence of two witnesses.
